FREQUENCY CONTROL APPARATUS FOR AN ATOMIC BEAM TUBE

Eugene F. Grant, Marblehead Neck, and Lawrence F. Fenton, Malden, Mass., assignors to National Company, Inc., Melrose, Mass., a corporation of Massachusetts
Filed Jan. 25, 1961, Ser. No. 84,880
10 Claims. (Cl. 331—3)

This invention relates to automatic frequency controls for frequency standards and more particularly it is concerned with apparatus for automatically tuning an electronic flywheel oscillator to the resonance frequency of an atomic beam tube or the like.

Frequency standards incorporating atomic beam tubes conventionally make use of a crystal controlled oscillator to provide a useful output signal of standard frequency. To regulate the frequency of the oscillator, a servo system is generally provided. By means of this servo system, the signal response of the beam tube is used to control the frequency of the oscillator which in turn is used in synthesizing the beam tube input signal.

As is well known to those skilled in the art, the frequency response which the beam tube exhibits has two components, a pedestal, and a series of symmetrical fluctuations superimposed thereon. The pedestal is often referred to as the Rabi curve and the superimposed component is known as the Ramsey pattern. As the central Ramsey peak is normally located at the midpoint of the pedestal, it follows that the overall response curve is substantially symmetrical about this peak which corresponds to the true resonance frequency of the beam tube.

A problem that arises in the design of a servo system to maintain the input frequency to the beam tube at resonance, that is locked on the centrally located peak, is the ambiguity introduced by the other maxima or side peaks in the Ramsey pattern. Especially is the problem acute when the frequency standard is first placed in operation and the beam tube input signal is displaced substantially from the central peak, as is normally the case. It also can happen after the standard is placed in operation, that the beam tube input signal frequency shifts to one of the side peaks as a consequence of some transient phenomenon, and locks onto this peak.

In patent application No. 59,925 filed October 3, 1960, in the name of Arthur Orenberg, there is disclosed an automatic frequency control system for an atomic frequency standard which offers a solution to this problem based on the use of two modes of servo control, a coarse and a fine control. For coarse control of the oscillator frequency, the signal applied to the beam tube is frequency modulated with a large frequency deviation encompassing essentially the entire pedestal or Rabi curve. This produces a fundamental component in the output of the beam tube at the frequency of the modulating signal, which approaches zero as the center operating frequency approaches resonance. This component is used to control the operation of a servo motor which roughly tunes the oscillator frequency. There is also produced in the output of the beam tube a second harmonic component which is a maximum at the true resonance frequency. When this second harmonic component reaches a value slightly less than this maximum signifying that the center operating frequency of the beam tube is very nearly the same as the true resonance frequency, a switching circuit initiates the fine mode of oscillator frequency control. For fine control, the signal applied to the beam tube is frequency modulated with a small deviation encompassing only the Ramsey pattern or a fraction thereof. This produces a more sharply defined fundamental component in terms of frequency dependence which is adapted

2

to control the operation of the servo motor and so also the oscillator frequency more precisely.

The main problem encountered with this system is that should the oscillator frequency become locked on a side peak, the system will not initiate the search for the central peak, unless additional means are provided for the purpose. Another disadvantage of this system is its dependence upon an absolute level of second harmonic signal since the amplitude of this signal is subject to change for various reasons independent of frequency. For example, operating temperature and ageing have an appreciable effect upon the sensitivity of the beam tube and of the electronic circuitry, and variations in sensitivity of course are reflected in the amplitude of the second harmonic as well as other frequency components of the beam tube output signal. Then too, with this scheme, an appreciable time delay is involved in the search for the true resonance frequency before the fine mode of control can be established and a useful timing signal obtained from the frequency standard.

Accordingly, the object of the present invention is to provide improved apparatus for placing an atomic frequency standard in operation at the true resonance frequency of the beam tube incorporated in the standard, and for maintaining operation at this frequency.

Another object is to provide a more reliable system of the above-mentioned character.

Yet another object is to provide a faster acting mode of control of the frequency of the standard which is adapted to place the standard in operation more rapidly and to afford closer supervision of its frequency.

A further object is to provide frequency control apparatus which does not add appreciably to the complexity of the frequency standard.

In brief, the present invention contemplates periodic frequency shifting of the beam tube input signal between two closely spaced frequencies and two relatively widely spaced frequencies. This is accomplished by means of sine wave or square wave frequency modulation of the beam tube input frequency between the desired narrow and wide frequency limits. The square wave FM is done by synthesizing the limit frequencies with single side-band techniques or by triangular phase modulation of the center frequency. In either case, the invention features the use of sampling circuits or gates which are synchronized with the frequency shifts of the beam tube input signal and which provide separate indications of the response of the beam tube to small and large frequency shifts. These indications in the form of direct current signals are operated upon separately in two distinct amplifier channels thereby to relate the effect of large frequency displacements from resonance, which are reflections of the Rabi curve, to the effect of small frequency displacements, which are reflections of the Ramsey pattern. Thereafter, the signals are combined in a summing network so as to provide a single composite signal which is adapted to drive the oscillator frequency to the resonance peak in a continuous fashion irrespective of the magnitude of any displacement error that is present initially. As in prior apparatus of a related character, the medium for controlling the crystal oscillator frequency is a servo system.

The novel features of the invention together with further objects and advantages will become apparent from the following detailed description and the drawings to which it refers. In the drawings:

FIG. 1 is a block diagram of the automatic frequency control apparatus according to the present invention;

FIG. 2 is a graphical representation of the direct voltage output from the beam tube as a function of frequency when the signal applied to the beam tube is unmodulated;

FIG. 3 is a graphical representation of the frequency modulations of the signal applied to the beam tube;

FIG. 4 is a graphical representation of sample voltages derived from the output of the beam tube under various on and off-resonance conditions;

FIG. 5 is a graphical representation of the signals found at certain points in the apparatus as a function of frequency displacement errors; and

FIG. 6 is a diagram of a synchronous detector for the sample voltages.

With reference now to the drawings and more particularly to FIG. 1, it will be observed that the numeral 11 designates the atomic beam tube employed in the frequency standard and numeral 12 refers to a frequency synthesizer and modulator. The function of frequency synthesizer and modulator 12 is to provide, by means of various frequency multiplying, dividing, and mixing operations, two output signals bearing a fixed frequency relation to the signal generated by a flywheel oscillator 13, preferably a crystal oscillator. One of these output signals has a useful output frequency for standard reference purposes, such as one megacycle per second. The other output signal has the capability of being matched in frequency to the atomic resonance frequency of the beam tube to which it is applied. For an atomic beam tube which makes use of the lowest atomic resonance of cesium, this frequency is 9192.6318 megacycles per sec. An ancillary function of the unit is to apply angle modulation to the beam tube input signal, that is either phase or frequency modulation which yields a square waveform to be described in detail hereinafter.

The output signal from the beam tube includes a direct current (D.C.) component together with an alternating current (A.C.) component whose frequency is determined by the modulating frequency. Preferably, a relatively low modulating frequency such as twenty cycles per second is used so as to afford sufficient time for transient phenomena to subside in the beam tube subsequent to the abrupt changes in frequency occasioned by the modulating signal. The output signal from the beam tube is applied to an A.C. amplifier 14 which serves two distinct signal channels hereinafter referred to as a Ramsey channel and a pedestal channel. The pedestal channel is seen to include a clamp device 16 which refers a selected portion of the beam tube output signal waveform to ground. The basic element of the clamp is a switching circuit responsive to timing pulses transmitted by way of a line 17 from a timing pulse and pattern generator 18. Also included in the pedestal channel is a biasing network and an A.C. amplifier 19. The biasing network in its most basic form includes direct voltage sources 21, 21', and diodes 22, 22'. As shown, the diodes are disposed in parallel circuits with their polarities opposite to one another, and the respective sources or batteries 21 and 21' are in series with the diodes to reverse bias them. Finally there is provided in the pedestal channel a unit 23 which performs the function of a synchronous detector under control of timing pulses on lines 24 and 25 from the timing generator. A synchronous detector unit 26 of like nature is disposed in the Ramsey channel, this unit being served by timing pulses on lines 27 and 28. Both units 23 and 26 will be described in more detail hereinafter in connection with FIG. 6.

D.C. signals derived by detector units 23 and 26 are combined in a summing circuit 27 and, as amplified in a D.C. amplifier 28, are used to control the operation of a servo motor 29. Motor 29 is mechanically coupled to a tuning element 13' incorporated in the crystal oscillator 13. By this means, fine adjustments are made in the crystal oscillator frequency.

The form of synchronous detector circuit contemplated for detector 23 is shown schematically in FIG. 6. From FIG. 6 it will be observed that the circuit includes two switches 31 and 32 responsive to pulse signals on lines 24 and 25, respectively. Connected through a resistor 33

and a capacitor 34 to one terminal each of the switches is the ungrounded line from amplifier 19 in the pedestal channel. When closed, switch 31 effectively grounds the capacitor 34. When switch 32 is closed, it serves to connect capacitor 34 to an integrating circuit including a resistor 36 and a capacitor 37. The output of the detector unit is derived from the capacitor 37, one side of which is also grounded. Various conventional electronic switching circuits incorporating either tubes or transistors can be used to implement the switches 31 and 32. In the Ramsey channel the detector 26 has the same configuration as unit 23, the resistor 33 of the Ramsey channel detector being connected directly to the output circuit of common A.C. amplifier 14.

Broadly speaking, the function of the synchronous detector in the pedestal channel is to derive a direct current signal which represents the variation in the beam tube output signal when the frequency of the beam tube input signal is shifted between the two more widely separated limits defined by the modulating signal. This is the frequency shift which is produced under wideband modulation conditions with a frequency swing approximately equal to the width of the pedestal, as shown in FIG. 3 between +6 and -6 kilocycles per sec. (kc.). Similarly, the function of synchronous detector 26 in the Ramsey channel is to derive a direct current signal which represents the variation in the beam tube output signal when the frequency of the beam tube input signal shifts between the two more closely spaced limits, between +250 and -250 cycles per sec. in FIG. 3. This is the frequency shift produced under narrow band modulation conditions with a frequency swing approximately equal to the width of the Ramsey pattern. The mentioned numbers for the pedestal and Ramsey width are typical for certain beam tube constructions, but can be different for other constructions. A more precise understanding of the manner in which the synchronous detectors operate will be gained from FIG. 1 where the frequency modulation waveform is shown opposite the line 41 on a smaller scale than that of FIG. 3. Also, the control pulses for the synchronous detectors are shown adjacent the lines 24, 25, 27, 28 over which they are transmitted, the spacing of the pulses with respect to one another and with respect to the frequency modulation waveform being representative of their actual time relation. Such signals can be generated through the use of conventional pulse circuit techniques incorporating multivibrator circuitry, for example.

From FIG. 1, it will be observed that the control pulses on lines 24 and 25, respectively, occur during terminal portions of the respective positive and negative going pulses representing the wideband frequency shifts of the beam tube input signal. During the portion of the positive going pulses contemporaneous with a pulse on line 24, switch 31 of detector unit 23 closes so that capacitor 34 becomes charged to the value of the beam tube output signal. In the case of a frequency displacement error of approximately 750 c.p.s. corresponding to point D in FIG. 2, the value to which capacitor 34 is charged at this time is 3.5 volts as defined by the 3.75 to 7.5 millisecond (ms.) portion of the curve D' in FIG. 4. Upon termination of the pulse on the line 24, switch 31 then opens. Subsequently, during the portion of the negative going modulation pulse contemporaneous with a control pulse on the line 25 (from 11.25 to 15 ms. in FIG. 4), switch 32 closes while the switch 31 remains open. If the value of the beam tube output signal is different than it was, as it is in the assumed case of a frequency offset of 750 c.p.s., current flows through the switch to ground charging the capacitor 37. Conversely, if it be assumed that no frequency displacement error exists which is the case represented by curve A' in FIG. 4, then no charging current flows through the capacitor and no direct current output signal is produced. In other words, curves A', B', D' in FIG. 4 indicate the changes in the levels of the

output signal from the beam tube under various conditions of offset defined by the corresponding points A, B, D, in FIG. 2. Preferably, the duration of the timing pulses should be at least half that of the modulation pulses in order to enhance the signal to noise ratio of the detected signals. However, the control pulse should begin only after the transient in the beam tube signal, which is initiated by the sudden change of frequency, has subsided to a negligible level.

By now, it should be apparent that during the intervals of from 18.75 to 22.5 and 26.25 to 30 milliseconds when the small amplitude frequency shifts occur, the synchronous detector unit 26 in the Ramsey channel is enabled to produce a D.C. output signal representing the variations in the amplitude of the beam tube output signal. At these times, it will be observed from FIG. 4 that the change in the beam tube output signal is much greater owing to the fact that the beam tube output changes more with a narrowband frequency swing than with a wideband frequency swing in the vicinity of its true resonance frequency. Preferably, the time constant defined by resistor 36 and capacitor 37 should be large compared with the time interval defined by one complete modulation cycle. The reason is that integration of the beam tube output signal during a number of sample periods can be effected in this way, which enhances the signal to noise ratio of the detected signal. Also the time constant defined by resistor 33 and capacitor 34 should be sufficiently large to cause good averaging of noise fluctuations which occur during a single sample period corresponding to one modulation pulse width.

In FIG. 5, curve R represents the amplitude of the D.C. signal derived by the synchronous detector 26 in the Ramsey channel as a function of frequency displacement error or offset. As is apparent, only displacement errors of one sense namely negative displacements in the direction of decreasing frequency have been illustrated for the sake of simplicity in the drawing. Thus, at the origin of the curve, corresponding to no offset, no detector signal is produced since the beam tube output signal is the same for a positive shift of 250 cycles per sec. as it is for a negative one. For very small displacement errors it will be observed that the detector signal increases with increasing frequency displacement. For example, it will be seen from FIG. 5 that a frequency swing about point B in FIG. 2 in the amount of ± 250 cycles per sec. the narrow band FM case with which the Ramsey channel is concerned, results in a detected signal having an amplitude of approximately three volts. When the offset exceeds approximately 250 cycles per sec., however, the effect of the frequency swing begins to decrease because the negative excursion of the beam tube signal frequency begins to embrace the response minimum shown at point C in FIG. 2. In fact, when the offset becomes approximately equal to 500 cycles per sec. corresponding to the location of the minimum, then the detector signal falls to zero owing to the symmetry of the beam tube frequency response for small frequency shifts above and below this point. Thereafter, the detector signal increases in the negative direction to a maximum at approximately 750 cycles per sec. corresponding to point D in FIG. 2 and once again disappears at approximately 1000 cycles per sec. where another maximum or side peak in the beam tube response occurs, as shown at E in FIG. 2. Finally, it will be observed that the signal detected in the Ramsey channel exhibits a maximum at F or approximately 1250 cycles per sec. where the slope of the frequency response of the beam tube undergoes a transition from concave to convex approximately midway between points E and G in FIG. 2; and another maximum at H where the final point of inflection occurs in the beam tube response curve of FIG. 2.

Curve P in FIG. 5 represents the amplitude of the signal derived by detector 23 in the pedestal channel as a function of frequency offset from the true resonance fre-

quency. In the region between the origin of the curve and approximately 200 cycles per sec., no output signal is developed by the detector because the beam tube output signal is of insufficient amplitude to overcome the effect of the biasing circuit in this channel. By this means, full control of the frequency correction process is left to the signal derived in the Ramsey channel whenever the frequency of the input signal to the beam tube is within the range occupied by the central resonance peak from approximately +200 to -200 cycles per sec. Otherwise, any asymmetry of the Ramsey pattern with respect to the pedestal would have an influence upon the frequency at which the system stabilized. Thereafter, with offsets of from 200 to approximately 500 cycles per sec., the pedestal detector signal exhibits a linear increase with increasing frequency displacement errors, manifesting the asymmetrical location of points on the pedestal skirts corresponding to frequencies six kilocycles per sec. above and below an offset center frequency in this region. The level of the pedestal detector signal at the limit of this region, namely 500 cycles per sec. below the true resonance frequency, is approximately 8 volts, a level greater than that produced in the Ramsey channel. This is due to the gain of amplifier 19 whereby control is given to the pedestal signal should the frequency of the beam input signal drift off the central resonance peak. Offsets of more than 500 cycles per sec. do not cause an appreciable change in the amplitude of the pedestal signal as amplifier 19 is adapted to saturate when this level is reached.

The combined signal resulting from the summation of both detector signals in the Ramsey and pedestal channels is represented by curve S in FIG. 5. This curve is seen to have the same general shape as curve R except that it is displaced upwardly with respect thereto because of the positive level which curve P adds. A primary attribute of curve S is that it has an appreciable magnitude of fixed sense throughout the range of frequency offsets illustrated, namely from zero to approximately eight kilocycles per sec. In consequence, the combined signal is adapted to drive the servo motor 29 and so also the frequency of oscillator 13 quickly into the region where the displacement error is less than approximately 200 cycles per sec. Also, since the slope of the curve is relatively linear from zero to 200 cycles per sec. the signal affords an optimum mode of servo control whereby a null balance can be obtained at zero displacement errors corresponding to the true resonance frequency of the beam tube. For frequencies above resonance, that is positive frequency displacement errors or offsets, the same curves P, R, S apply except that a polarity reversal occurs. The polarity of the signal determines the direction of rotation of the servo motor whereby a correction of the proper sense is initiated to eliminate a displacement error.

Although the invention has been described in connection with a single preferred embodiment, it will be apparent to those skilled in the art that various modifications and alternatives within the spirit and scope of the invention are possible. For example, instead of the mechanically tuned capacitor a mechanically tuned inductor can be employed to control the oscillator frequency. In fact, the D.C. voltage can be used directly, without a servo motor, to change the capacity of a voltage variable capacitor (varicap), or the D.C. current can be used to change the inductance of a saturable inductor. Furthermore, several narrow band sweep cycles can be employed for each wide band cycle or vice versa. It is also contemplated that triangular phase modulation of the beam tube input signal can be used to obtain the desired frequency modulation waveform. Accordingly the invention should not be deemed to be limited to the details of what has been described herein by way of illustration, but rather it should be deemed to be limited only by the scope of the appended claims.

What is claimed is:

1. Frequency control apparatus for use with an atomic

beam tube, said apparatus comprising means for producing a radio frequency signal and applying it to said beam tube, means for periodically shifting the frequency of said beam tube input signal between two closely-spaced values and two relatively more widely spaced values, means for deriving a first direct current signal as a function of the amplitude variation of the beam tube output signal when the frequency of the beam tube input signal is shifted between said closely-spaced values, means for deriving a second direct current signal as a function of the amplitude variation of the beam tube output signal when the frequency of the beam tube input signal is shifted between said widely-spaced values, means to produce a composite signal as a function of the sum of said first and second D.C. signals, and means to control the center frequency of the beam tube input signal in response to said composite signal.

2. Frequency control apparatus for use with an atomic beam tube, said apparatus comprising means for producing a radio frequency signal and applying it to said beam tube, means to produce square-wave modulation of the frequency of said beam tube input signal at alternating high and low levels, means for deriving a first direct current signal as a function of the beam tube output signal during a cycle of low level modulation of the frequency of the beam tube input signal, means for deriving a second direct current signal as a function of the beam tube output signal during a cycle of high level modulation of the frequency of the beam tube input signal, means to produce a composite signal as a function of the sum of said first and second direct current signals, and means to control the center frequency of the beam tube input signal in response to said composite signal.

3. Frequency control apparatus for use with an atomic beam tube, said apparatus comprising means for producing a radio frequency signal and applying it to said beam tube, means to produce square wave frequency modulation at alternating high and low levels by synthesizing and switching the frequency of said beam tube input signal, means for deriving a first direct current signal as a function of the beam tube output signal during a cycle of low level modulation of the frequency of the beam tube input signal, means for deriving a second direct current signal as a function of the beam tube output signal during a cycle of high level modulation of the frequency of the beam tube input signal, means to produce a composite signal as a function of the sum of said first and second direct current signals, and means to control the center frequency of the beam tube signal in response to said composite signal.

4. Frequency control apparatus for use with an atomic beam tube, said apparatus comprising means for producing a radio frequency signal and applying it to said beam tube, said first named means including a crystal oscillator with a mechanically tunable element for varying the frequency of the oscillator, means to produce square-wave modulation of the frequency of said beam tube input signal at alternating high and low levels, means for deriving a first direct current signal as a function of the beam tube output signal during a cycle of low level modulation of the frequency of the beam tube input signal, means for deriving a second direct current signal as a function of the beam tube output signal during a cycle of the high level modulation of the frequency of the beam tube input signal, means to produce a composite signal as a function of the sum of said first and second direct current signals, a servo motor coupled to the mechanically tunable element and means to control the operation of the servo motor in response to said composite signal.

5. Frequency control apparatus for use with an atomic beam tube, said apparatus comprising means for producing a radio frequency signal and applying it to said beam tube, means to produce square-wave modulation of the frequency of said beam tube input signal at alternating high and low levels, a pair of signal transmission channels for processing of the output signal from said beam tube,

means to produce an increased amount of amplification of the output signal transmitted by the second of said channels relative to that transmitted by the first channel, a first synchronous detector disposed in said first channel for deriving a first direct current signal as a function of the beam tube output signal during cycles of low level modulation of the frequency of the beam tube input signal, a second synchronous detector disposed in said second channel for deriving a second direct current signal as a function of the beam tube output signal during cycles of high level modulation of the frequency of the beam tube input signal, means to produce a composite signal as a function of the sum of said first and second direct current signals, and means to control the center frequency of the beam tube input signal in response to said composite signal.

6. Frequency control apparatus for use with an atomic beam tube, said apparatus comprising means for producing a radio frequency signal and applying it to said beam tube, means to produce square-wave modulation of the frequency of said beam tube input signal at alternating high and low levels, a pair of signal transmission channels for processing of the output signal from said beam tube, an amplifier disposed in said second channel to increase the amplitude of the signal transmitted thereby relative to that transmitted by said first channel, a biasing network disposed in said second channel to prevent the transmission of signals whose amplitude is less than a predetermined minimum, a first synchronous detector disposed in said first channel for deriving a first direct current signal as a function of the beam tube output signal during cycles of low level modulation of the frequency of the beam tube input signal, a second synchronous detector disposed in said second channel for deriving a second direct current signal as a function of the beam tube output signal during cycles of high level modulation of the frequency of the beam tube input signal, means to produce a composite signal as a function of the sum of said first and second direct current signals, and means to control the center frequency of the beam tube input signal in response to said composite signal.

7. Frequency control apparatus for use with an atomic beam tube, said apparatus comprising means for producing a radio frequency signal and applying it to said beam tube, means to produce square-wave modulation of the frequency of said beam tube input signal at alternating high and low levels, a pair of signal transmission channels for processing of the output signal from the beam tube, a first synchronous detector disposed in said first channel for deriving a first direct current signal as a function of the beam tube output signal during cycles of low level modulation of the frequency of the beam tube input signal, said synchronous detector including means to sample and store the beam tube output signal voltage during the first half of the low level modulation cycles and means to sample and compare the beam tube output signal voltage during the second half of the low level modulation cycles with that having been stored from the first half of the corresponding cycles, a second synchronous detector disposed in said second channel for deriving a second direct current signal as a function of the beam tube output signal during cycles of high level modulation of the frequency of the beam tube input signal, said second synchronous detector including means to sample and store the beam tube output signal voltage during the first half of the high level modulation cycles and means to sample and compare the beam tube output signal voltage during the second half of the high level modulation cycles with that having been stored from the corresponding first half cycles, a summing circuit to produce a composite signal representative of the sum of said first and second direct current signals, and means to control the center frequency of the beam tube input signal in response to said composite signal.

8. Apparatus as claimed in claim 7 wherein said means

to sample and compare includes an integrating circuit for averaging of the direct current signals detected during a plurality of modulation cycles.

9. Apparatus as claimed in claim 7 wherein said first synchronous detector includes means to clamp to zero level the output signal voltage in one half of the low level modulation cycle and said second synchronous detector includes means to clamp to zero level the output signal voltage in one half of the high level modulation cycle.

10. Frequency control apparatus for use with an atomic beam tube, said apparatus comprising means for producing a radio frequency signal and applying it to said beam tube, said first-named means including a crystal oscillator with a tunable element for varying the frequency of the oscillator, means to produce square-wave modulation of the frequency of said beam tube input signal at alternating high and low levels, a pair of signal transmission channels for processing of the output signal from the beam tube, an amplifier disposed in said second channel to increase the amplitude of the signals transmitted by said second channel during the high level modulation cycles relative to the amplitude of the signals transmitted by said first channel during the low level modulation cycles, a biasing network disposed in said second channel to prevent the transmission of signals whose amplitude is less than a predetermined minimum, a synchronous

detector disposed in said first channel for deriving a first direct current signal as a function of the beam tube output signal during cycles of low level modulation of the frequency of the beam tube input signal, said first synchronous detector including means to sample and store the beam tube output signal voltage during the first half of the low level modulation cycles and means to sample and compare the signal voltage during the second half of the low level modulation cycles with that having been stored from the corresponding first half cycles, a second synchronous detector disposed in said second channel for deriving a second direct current signal as a function of the beam tube output signal during cycles of high level modulation of the frequency of the beam tube input signal, said second synchronous detector including means to sample and store the output signal voltage during the first half of the high level modulation cycles and means to sample and compare the signal voltage during the second half of the high level modulation cycles with that having been stored from the corresponding first half cycles, a summing circuit to produce a composite signal representative of the sum of said first and second direct current signals, a servo system coupled to the tunable element, and means to control the operation of the servo system in response to said composite signal.
